UNITED STATES PATENT OFFICE

RICHARD WILLIAMSON, OF CHICAGO, ILLINOIS, ASSIGNOR, BY MESNE ASSIGNMENTS, TO BEARDSLEE CHANDELIER MANUFACTURING CO., OF CHICAGO, ILLINOIS, A CORPORATION OF DELAWARE

LIGHTING FIXTURE

Application filed January 26, 1928. Serial No. 249,568.

This invention relates to lighting fixtures and its object is to provide a neat and attractive fixture of simple construction for distributing the light from a lamp to the best advantage and produce a desirably soft, distributed and effective illumination.

The invention also has for its object to combine the fixture frame, the shade and the lamp in a novel manner to throw a flood light effect upward on and above the fixture, and a soft distributed light around the fixture and a concentrated light downward upon a dining table, a card table or other furniture beneath the fixture.

15 And a further object of the invention is to confine the number of parts to a minimum, and to provide means whereby the shade is held in place on the fixture arm by structural engagement therewith and is prevented from 20 displacement from the fixture by a novel arrangement of the lamp with respect to the shade and the fixture arm.

In the accompanying drawings I have illustrated a selected embodiment of the invention wherein

Fig. 1 is a sectional elevation of a portion of a fixture and embodying my invention.

Fig. 2 is a top plan view of the structure shown in Fig. 1.

30 Fig. 3 is a perspective view of the shade.

Figs. 4-9 are sectional views showing other forms of the invention.

The fixture may comprise one or any number of arms which may be made in any suitable form and construction and of any desired material. I have chosen for illustration an arm of a fixture comprising a plurality of arms of the kind which is usually suspended from the ceiling of a dining room and above 35 a table, or from the ceiling of a living room, and is generally made of cast or suitably stamped sheet metal; but I do not restrict the invention to this or any other particular type of fixture because it will readily be appreciated as the invention is better understood that it is capable of embodiment in other fixtures with equally satisfactory results.

Therefore I consider it sufficient to show 50 and describe the arm 4 of the fixture in a

general way only as provided with an upright bracket 5 for supporting the lamp socket 6 to which it is securely fastened. This socket projects substantially horizontally above the arm and sufficiently close to the arm so that the lamp 7 will project partly into or close to an opening 8 in the arm.

The shade shown in Fig. 3 has a curved front 9, rearwardly extending sides 10, an open back 11, an open top 12, a closed bottom 13 having a partly convex portion 14 which fits with a reasonable degree of snugness in the opening 8 in the arm of the fixture, Figs. 1, 2. In this embodiment of the invention the shade will throw a flood-like effect up, upon and above the fixture and soften and distribute the light around about the fixture and concentrate a soft light down through the opening in the fixture. The shape of the shade is such that the lamp cannot conveniently be engaged with the socket after the shade has been arranged in place on the fixture arm and hence the lamp must be screwed into the socket first and the shade arranged in position thereafter. Also, the shape of the shade is such and the arrangement of the lamp with respect to the arm and the opening therein is such that the shade cannot be slid into place with a horizontal or even a substantially horizontal movement, but must be tilted at a considerable angle and then slipped in between the lamp and the arm with the convex portion entering the opening. When the shade is properly arranged on the arm, its bottom will rest flatly thereon and the convex portion will seat in the opening 8. The lamp is arranged to project partly into the concavity at the back of the convex portion of the bottom of the shade so that by reason of the engagement of the convex portion with the opening in the arm and the arrangement of the lamp with respect to the convex portion the shade will be prevented from moving laterally or in a substantially lateral movement on the arm. It is only possible to apply or remove the shade by tilting it at a considerable angle over the lamp, and it is not likely that under any ordinary conditions the shade will ever become tilted to such an angle unless it is so tilted deliber- 100

ately for the purpose of engaging or disengaging it. Thus the shade is held firmly and securely on the fixture arm without the provision of fastening means which are objectionable because of the difficulty of adjusting them, the liability of breaking the shade, the general insecurity of such means as are commonly employed for this purpose, and many other objections known in the trade. 5 The absence of fastening devices facilitates 10 cleaning the fixture and replacing the lamp by making it easy to remove the shade. This is important with wall fixtures, but it is more important with ceiling fixtures which are not 15 so accessible.

15 In Fig. 4 the shade is like that shown in Fig. 3 except that it has a flat bottom 15; in Fig. 5 the shade also has a flat bottom 16 and the sides 17 are of the same height as the 20 front 18; in Fig. 6 the shade has a flat bottom 19 and a flat top 20; in Fig. 7 the shade is like that shown in Fig. 5 except that the bottom has a convex portion 21; in Fig. 8 the shade is like that shown in Fig. 6 except that 25 the bottom has a convex portion 22; and in Fig. 9 the shade has an open bottom and a flat top 23. The shades shown in Figs. 4-8 are seated on the arm as heretofore described but the shade of Fig. 9 may be seated by passing it down over the lamp in a substantially 30 vertical direction. The shades may be spaced from the rim 24 of the arm as shown in Figs. 1, 2, 7 and 8 or they may be seated close to or in engagement with the arm as shown in Figs. 35 4, 5, 6 and 9.

40 In all of these embodiments of the invention there is a co-operation between an arm having an opening, a lamp arranged above the opening, and a shade seated on the arm about the lamp which results in an efficient distribution of light from the lamp to produce a superior illuminating effect.

45 It is desirable to mount the socket 6 in the bracket 5 as close as possible to the arm 4 so that it will be hidden from view from below the fixture by the arm and the flange 24 thereon, as shown in Figs. 1 and 9, and it may be necessary in some embodiments of the invention to tilt the socket slightly, as shown in 50 broken lines in Fig. 7.

55 I contemplate making the shade of translucent glass with or without decorations, but it may be made of other kinds of glass, or combinations thereof; or it may be made of parchment, pigskin or other material suitable for the purpose. I do not restrict my invention to the particular forms and construction herein shown and described, nor to the particular arrangement of parts for all purposes, but I 60 reserve the right to make any changes therein that may be desirable to satisfy various conditions and within the scope of the following claims.

65 I claim:

65 1. In a lighting fixture, the combination of

a supporting arm provided with an opening therein, a lamp supported in a substantially horizontal position on said arm and projecting above said opening, and a shade seated on the arm and having a convex portion arranged in said opening, the convex portion fitting in said opening to prevent lateral movement of the shade on the arm and the lamp projecting partly in the concave back of the convex portion of the shade to prevent accidental displacement of the shade. 70

2. In a lighting fixture, the combination of a substantially horizontal supporting arm provided with an opening therein, an up-standing bracket on said arm spaced from said opening, a lamp socket supported in a substantially horizontal position on said bracket, a lamp engaged with said socket and projecting above said opening, and a shade closed at the front and sides, open at the top and back and having a closed bottom with a convex portion, said convex portion projecting downwardly through said opening in the arm and said lamp projecting into the concave back of said convex portion. 80

3. In a lighting fixture, the combination of a bracket arm having a horizontally disposed seat portion and an opening in the bottom wall of said seat portion, a shade surrounding said opening and removably supported entirely upon the seat and having a side opening, a socket mounted on said arm outside of said shade and a lamp in said socket extending substantially horizontally through the side opening into the shade and positioned directly above the seat opening. 90
